CLOG

Joseph P. Famolare, Jr., Florence, Italy, assignor to Famolare, Inc., New York, N.Y.

Filed Mar. 22, 1972, Ser. No. 237,243

Term of patent 14 years

Int. Cl. D2—04

U.S. Cl. D2—292

FIG. 1

FIG. 2

FIG. 3

FIG. 4

FIG. 5

FIG. 6

FIG. 1 is a side elevational view of a clog showing my new design;

FIG. 2 is a top plan view thereof;

FIG. 3 is a side elevational view of the side opposite that shown in FIG. 1;

FIG. 4 is a bottom plan view;

FIG. 5 is a rear elevational view; and

FIG. 6 is a front elevational view.

I claim:

The ornamental design for a clog, substantially as shown and described.
